UNITED STATES PATENT OFFICE.

GILBERT L. CROWELL, JR., OF ARLINGTON, NEW JERSEY, ASSIGNOR TO DOMINICK & HAFF, OF NEW YORK, N. Y., A JOINT STOCK COMPANY, OF NEW YORK.

DESIGN FOR A DISH OR SIMILAR ARTICLE.

No. 38,614.

Specification for Design.

Patented June 11, 1907.

Application filed May 10, 1907. Serial No. 373,018. Term of patent 7 years.

To all whom it may concern:

Be it known that I, GILBERT L. CROWELL, a citizen of the United States, residing at Arlington, in the county of Hudson and State of New Jersey, have invented a new and original Design for Dishes or Similar Articles, of which the following is a specification, reference being had to the accompanying drawing, forming a part thereof.

The figure is a plan view of the dish showing my new design.

I claim

The ornamental design for a dish or similar article as shown.

GILBERT L. CROWELL, JR.
